UNITED STATES PATENT OFFICE

WESLEY J. SHAW, OF HAVERHILL, AND MILES E. BASTOW, OF GROVELAND, MASSACHUSETTS, ASSIGNORS TO NEW ENGLAND WOOD HEEL CO., OF HAVERHILL, MASSACHUSETTS, A CORPORATION OF MASSACHUSETTS

GUARD FOR WOOD-HEEL TURNING MACHINES

Application filed October 29, 1927. Serial No. 229,729.

The present invention relates to safety devices for protecting operators from accidental contact with cutting knives, and more particularly to guards for the cutters of wood-heel turning machines.

The nature and the objects of the invention will be explained in connection with the accompanying drawings, in which Fig. 1 is an elevation of a portion of a wood-heel-turning machine showing one embodiment of the present invention; Figs. 2 and 3 are sections taken upon the lines 2—2 and 3—3 of Fig. 1, respectively, looking in the direction of the arrows; Fig. 4 is a plan; and Fig. 5 is a view, similar to Fig. 1, showing one of the guards uncovering its cutter.

One of the operations connected with the manufacture of wood heels from wood-heel blocks or blanks 2 consists in shaping opposite sides of the block. To this end, the block is clamped between lower and upper jaws 4 and 6 of a clamp 8 that is mounted upon a jack 24, and its opposite sides are successively presented to the action of two horizontally-spaced, turning cutters 10 and 12 that rotate at high speed around vertical axes 7 and 9. In the drawings, the wood heel is illustrated as it appears after the cutters 10 and 12 have already performed their turning operations. Originally, however, at the time that it is first placed in the clamp 8, it is in the form of an unshaped wood block, except that the breast 11 has previously been grooved. The jack 24 may be swung by the operator horizontally over a curved track 14 by means of a handle 16. When the jack is swung in one direction, the wood block will be presented to the cutter 10; and when swung in the opposite direction, to the cutter 12. In order to permit of such swinging movement, the jack 24 is carried by a horizontally disposed arm 25 that is fixed by set screws 27 or the like to a rod 20. The rod 20 is journaled in vertically disposed bearings 17 of the base 18 of the machine, intermediately between the cutters 10 and 12. The jack 24 is fixed to a rod or shaft 22 that is journaled in bearings 30 of the arm 25. The arm 25, therefore, acts as a kind of link between the rods 20 and 22. It is fixed to the swinging rod 20 but permits

free rocking movement of the rod 22 in order to permit swinging movement of the jack 24 about the axis of the rod 22 in the bearings 30. The jack is thus horizontally swingable with the rod 20 about the vertical axis of the latter from an intermediate position between the cutters, as illustrated in the drawings, toward either cutter 10 and 12; and after the jack has been swung all the way around to one cutter or the other, it is rocked about the vertically disposed rod or shaft 22, so as to present successive portions of the side of the heel block to the cutter and thus turn the whole side from the breast 11 outward.

As the jack 24 is swung by the operator over the track 14, a roller 29, that is attached to the jack 24, engages the track 14 to tilt the jack 24 about a horizontal pivot pin 26. The pivot pin 26 is carried by an arm 28 that extends out from the upper end of the rod 22. The pivot pin 26 is also movable vertically, so as to raise and lower the heel block as it is acted on by the cutters. Such vertical movement is permitted by having the rod 22 vertically movable in the bearings 30 of the arm 25. The vertical movement of the rod 22 is automatically effected during the swinging of the jack 24 by a roller 32 that is mounted at the lower end of the rod 22 so as to ride over a second curved track 34. As the jack is swung back and forth, first toward the cutter 10, and then toward the cutter 12, the track 34 causes the pivotal point 26 to rise and fall, and the track 14 causes the roller 25 to rise and fall. The ultimate composite movement, in connection with the shape of the cutters 10 and 12, determines the resulting shape of the heel. The machine, as so far described, is of well-known type, and the purpose of this brief description is merely to provide a setting for the features of novelty about to be described.

Though both cutters 10 and 12 are continuously in operation, only one cutter at a time is doing any actual cutting; and for a great portion of the time, the jack is in the intermediate position, neither cutter being then in use. At the time that the jack has been swung around to either the cutter 10 or the cutter 12, the operator's attention is concentrated on that particular cutter, and there is little

danger, therefore, of his accidentally placing his hand in contact therewith, or otherwise becoming injured thereby. Whichever cutter is thus concentrated upon, however, the other cutter is receiving no such attention, and may cause injury, either to the operator himself or to a fellow workman. When the jack occupies its intermediate position, furthermore, both cutters are a source of accidental danger, and it is by no means an uncommon experience for even the most experienced turners to reach a hand absent-mindedly toward one cutter or the other, while clamping and unclamping the blocks.

15 According to the present invention, therefore, novel means are provided for guarding against injury from both cutters when the jack occupies its intermediate position; and for guarding against injury from either cutter when the operator is presenting a heel block to the other cutter. Separate guards 36 and 38, one for each cutter, are preferred, the guards being interposed between both cutters 10 and 12 and the clamp 8 when the jack occupies its intermediate position, and one or the other guard being automatically movable out of its interposed position when the operator swings the jack over from the intermediate position toward the corresponding cutter.

20 The guards are so designed as completely to enclose their respective cutters, and are connected with the operating mechanism of the machine so that the swinging movement of the jack automatically effects movement of the guards. A guard of such completely enclosing type ensures against accident even to others than the operators. It is preferred to effect the movement of the guards from an end of the swinging rod 20.

25 Normally, when the jack occupies its mid-position, the guards 36 and 38 occupy their cutter-enclosing or protecting position. When the jack is swung from the intermediate position towards the left-hand cutter 10, the guard 38 becomes automatically raised, as shown in Fig. 5, so as to expose the cutter 10 and permit its shaping one side of the wood-heel block 2. When the jack is moved in the opposite direction from its mid-position, toward the cutter 12, the guard 36 will be similarly raised to permit the cutter 12 to operate on the opposite side of the block 2. The guards are returned to their normal position by gravity.

30 In order to effect the raising of the guards, they are pivoted to swing in vertical planes about horizontal pivots 66 and 68, respectively, each fixed near one of the cutters. The guards are provided with an arm 70 and 72, respectively, adapted to be engaged by pins 74 and 76, respectively, that extend out from a horizontally disposed rocking spindle 78. The front end of the spindle is provided with a cam 80 that is disposed between two vertically disposed pins 82 and 84 that stand up

from the upper end of the swinging rod 20. When the jack is swung over the track 14 by the handle 16, therefore, causing the rod 20 to swing therewith, the spindle 78 will swing to correspond. When the spindle 78 occupies the position illustrated in Fig. 5, the guard 38 will accordingly be raised. When the spindle 78 is returned to the mid-position, along with the jack 24, the guard 38 will be lowered by gravity towards its normal or protecting position, illustrated in Figs. 1 to 4. Any further movement of the spindle 78 in the same direction will have no effect upon the guard 38.

Such further movement will, however, effect the raising of the guard 38 through the pins 74 and 76. When the spindle 78 is returned to the mid-position, the guard 38 will be returned by gravity to its normal position, further movement beyond the mid-position of the spindle 78 having no effect upon the guard 38.

The machine is provided with a hood 86, shown in Fig. 4 (but omitted, for clearness, from the remaining views), enclosing the cutters and parts of the guards. The wood dust shavings, etc. are drawn by pneumatic pressure through this hood. The hood is provided with openings or slots 88 to permit the above-described movement of the guards therethrough.

Other modifications, too, will occur to persons skilled in the art, and all such are considered to fall within the spirit and scope of the invention, as defined in the appended claims.

What is claimed is:

1. A heel-turning machine having, in combination, two horizontally spaced cutters for respectively turning opposite sides of a heel block, a clamp for holding the heel block, a jack upon which the clamp is mounted, means for swinging the jack from an intermediate position between the cutters toward either cutter, a pivot fixed near each cutter, a hooded guard pivoted to swing about each pivot so as to enclose and uncover the respective cutters, the guards enclosing the respective cutters when the jack occupies the intermediate position, each guard having an extension on the other side of its pivot, and means for engaging the respective extensions to pivot each guard to uncover its cutter when the jack is swung from the intermediate position toward the corresponding cutter.

2. A heel-turning machine having, in combination, two horizontally spaced cutters for respectively turning opposite sides of a heel block, a clamp for holding the heel block, a jack upon which the clamp is mounted, means for swinging the jack from an intermediate position between the cutters toward each cutter, a guard for each cutter, the guards being interposed between the

cutters and the clamp when the jack occupies the intermediate position and each being pivoted to swing in vertical planes about a horizontal pivot into and out of interposed positions, and means for pivoting each guard out of its interposed position when the jack is swung from the intermediate position toward the corresponding cutter.

3. A heel-turning machine having, in combination, two spaced-apart cutters for respectively turning opposite sides of a heel block, a clamp for holding the heel block, a jack upon which the clamp is mounted, a swinging rod intermediately disposed between the cutters and to which the jack is fixed so as to swing with the rod about the axis of the rod from an intermediate position between the cutters toward either cutter, a horizontally disposed spindle adapted to be rocked in opposite directions in accordance with the direction of swinging movement of the jack from the intermediate position toward either cutter, means carried by the swinging rod for rocking the spindle, a guard for each cutter, the guards being interposed between the cutters and the clamp when the jack occupies the intermediate position, and each being pivoted to swing in directions outward out of, and inward into, interposed position, and means carried by the spindle for engaging the guards to cause each guard to pivot in a direction outward out of interposed position when the jack is swung from the intermediate position toward the corresponding cutter.

In testimony whereof, we have hereunto subscribed our names this 26th day of October, 1927.
